FULL-FASHIONED HOSIERY

John E. Quinn, Philadelphia, Pa.

Application November 12, 1938, Serial No. 239,925

10 Claims. (Cl. 66—185)

This invention relates to hosiery, particularly to full-fashioned hosiery, and is confined to the foot portion thereof.

This is a continuation in part of my application Serial No. 73,372, filed April 8, 1936.

Women's stockings in the usual sizes are oftentimes of such size and nature that feet to which they are to be fitted fall between the regular sizes and on that account quarter sizes have been suggested which will entail apparent hardships on the retailer. That is to say, if he were required to provide quarter sizes in the various lines which he carries, additional stock would be necessary, so that he would be compelled to invest large sums in additional stock.

This application is, therefore, concerned with the problem of overcoming the inconvenience attending the present sizes of stockings and with the advantages attending a stocking with the 20 foot whose flexibility will adjust itself to the desired sizes.

The object of the present invention is to provide a stocking with a reinforced foot portion so constructed that it will adapt itself to feet 25 of incidental sizes.

A further object of the present invention is to produce a stocking which while being conventional in construction will have one or more of its reinforced foot portions so arranged as to 30 provide stretchability in non-consequential portions, thereby to enable the stocking to fit feet of varying sizes.

A further object is to provide a stocking 35 wherein the toe part may be heavily plated over the toes, around the sides of the foot and under same while still combining therewith the features of stretchability.

A still further object is to provide a stocking 40 wherein the usual diamond point narrowings are eliminated, and flexibility provided by narrowings through lace work areas.

In my United States application hereinbefore referred to, I have discussed and described a 45 stocking provided with a foot having a portion of alternate tight and loose courses whereby stretchability is provided.

According to the invention, the full-fashioned stocking blank having a leg and instep of normal knitting and a reinforced foot, has an area in 50 said foot made up of alternate blocks having all loose knit loops and intermediate blocks having all tight knit loops with portions adjacent the outer edges of the blank and extending the full length of said alternate blocks wherein each course is composed of loose loops. The loose

course areas may be provided with an additional reinforcing thread. The toe portion may be narrowed through lace stitches substantially near and parallel with the selvage edges of the toe, and an additional reinforcing thread may be 5 knitted into the area between the lace stitches. If desired, the stocking may be narrowed in the conventional manner and an extra reinforcing thread knitted into the entire toe or the entire toe may be composed of alternate tight and loose 10 courses with an extra reinforcing thread knit into the loose courses only.

The drawings illustrate an embodiment of the invention and the views therein are as follows:

Figure 1 is a developed partial view of a full-fashioned stocking blank showing an arrangement of loosely knitted areas to provide the required stretchability.

Figure 2 is a fragmentary diagrammatic view illustrating the ordinary reinforced tightly 20 knitted loops and an additional reinforcement in the loosely knitted loops which form the loosely knitted areas shown in the blank of Figure 1.

Figure 3 is a fragmentary view of a stocking made from the blank shown in Figure 1 illustrating how the tight loop and loose loop areas appear in the finished foot.

Figure 4 is a view similar to Figure 3 showing another arrangement of tight loop and loose 30 loop areas.

Figure 5 is a fragmentary view of the toe of the foot showing still another arrangement of alternating tight loop and loose loop areas.

Figure 6 is an enlarged fragmentary view of the toe of the stocking blank showing the arrangement of knitting in the toe of Figure 4.

Figure 7 is a like view showing the arrangement of the knitting in the toe of Figure 5.

Figure 8 is a view similar to Figure 6 showing the narrowing through lace work extending up to 40 the selvage on both sides of the blank, and

Figure 9 is a like view illustrating a conventional narrowed toe knitted with alternate tight and loose courses and with an additional reinforcing in the loose courses only.

Referring to Figures 1, 2 and 3, the stocking blank is made up of a leg 11, an instep 12 of normal knitting and a foot 13 of reinforced knitting. The foot has a heel 14, a sole 16 and a toe 17. The sole 16 has an area 18 adjacent to and parallel with each selvage 19 and knitted with loose loops 20, shown in Figure 2. This loosely knitted area 18 is in the form of a strip extending lengthwise of the foot and along each selvage edge of the blank. Loosely knitted areas 21 extend from 50 55

each area 18 sidewise of the foot toward the instep, leaving regular reinforced knitted areas 22 which are knitted with the regular reinforced tight loops 23 diagrammatically illustrated in Figure 2. These alternate areas 21 and 22 appear as blocks in the finished foot, shown in Figure 4, and permit stretching in either direction when placed on the foot of the wearer.

The reinforcing in heel 14, toe 17 and blocks 22 10 may be the conventional reinforcing now in common use, such as for example, a seven-strand thread knitted with a four-strand or other normal knitting strand of the instep 12. Of course, it will be understood that the seven-strand thread 15 and four-strand thread referred to are merely illustrative and other types of threads may be employed as found most expedient for the particular conditions desired.

In the loose loop areas 18 and 21 which have 20 the regular reinforcing therein, there may be an additional reinforcing thread 24, as shown in Figure 2. This additional reinforcing thread in the loosely knitted areas makes them as durable against wear as the tightly knitted areas without 25 impairing the stretchability.

Figures 4 and 6 show a construction wherein the loosely knitted strip areas 18 adjacent the selavage edge 19 extend lengthwise to the end of the toe in the form of narrowings as indicated at 30 26 in Figures 4 and 6, and Figure 4 shows this strip extending up to the top of the heel as indicated at 27. The narrowings 26 are knitted through lace work 28 parallel to the selavage edge 29 of the toe. From the lace work 28, blocks 31 35 of loosely knitted loops extend partway across the toe. From the loosely knitted part 27 of the heel, as shown in Figure 4, blocks 32 of loosely knitted loops extend inwardly. The instep is knitted with the regular tightly knit loops, and 40 the sole may or may not be arranged as shown in Figures 1 and 3. The lace improves the appearance of the stocking when on display, and adds to the stretching quality of the foot, while at the same time permits heavier plating between the 45 lace narrowings to strengthen the fabric which extends over the toes, around the sides of the toes and under the same.

Figure 2, which is diagrammatic, has tightly knit courses 23 and these courses are intended to 50 represent the combined thread like that of the leg or instep and the regular reinforcing thread or threads, while the courses 20 represent loose loops having the same threads as the courses 23 and an additional reinforcing thread 24.

55 In the toe shown in Figures 5 and 7 the loose loop areas are in the form of strips 33 extending across the toe between the lace work 28. The remaining portion of the toe between the lace work 28 and in the narrowing 34 is knitted with the conventional tight loop reinforced knitting. The loose loop areas 26, 27, 31, 32 and 33 may all be provided with an additional reinforcing thread 24 shown in Figure 2.

60 In Figure 8, I have shown an arrangement of knitting in the toe of a stocking in which each of the narrowings 36 is in the form of lace extending to the selavage edge 37. The area 38 between the lace narrowings may be of ordinary 70 tight knitting in which is introduced an additional reinforcing thread. A stocking having this type of knitting provides a reinforcing around the toes of the wearer where it is mostly required, and places the lace narrowing strips under the 75 toes where wear is not severe. A stocking with a

toe of this type will wear longer and will stretch sufficiently to conform to irregular sizes of feet.

In Figure 9, I have shown an arrangement of toe wherein narrowings 39 are of the conventional diamond point, and the toe has alternate 5 courses of tight loops and loose loops. The entire area of the toe has the conventional reinforcing except that the loose loop courses have an additional reinforcing thread. The loose loop courses are diagrammatically indicated by the 10 heavy lines 41, and the tight loop courses by the light lines 42. The use of loose loop courses with narrowings of this type, permits knitting the additional reinforcing thread from selavage to 15 selavage. This additional reinforcing thread in the loose loop courses makes them as strong against wear as the tight loop courses. A stocking toe is thus provided of a durable character which has a high degree of stretching quality.

Of course, the foot construction here described and the kind of yarn spoken of may be varied in many ways without departing from the inventions herein set forth and hereafter claimed.

The invention is hereby claimed as follows:

1. A full-fashioned stocking blank having a 25 leg and instep of normal knitting and a reinforced foot, said foot having an area thereof made up of alternate blocks having all loose knit loops and intermediate blocks having all tight knit loops, and portions adjacent the outer edges of said blank and extending the full length of said alternate blocks wherein each wale is composed of loose loops.

2. A full-fashioned stocking blank having a 35 leg and instep of normal knitting, a reinforced heel part, a reinforced sole part, a reinforced toe part, one or more of said parts having portions adjacent the outer edges of said blank and extending the full length of the said part or parts wherein each wale is composed of loose loops and 40 having within said part or parts alternate blocks having all loose knit loops and intermediate blocks having all tight knit loops.

3. A full-fashioned stocking blank having a 45 leg and instep of normal knitting and a reinforced foot, said foot having an area thereof made up of alternate blocks having all loose knit loops and intermediate blocks having all tight knit loops, portions adjacent the outer edges of said blank and extending the full length of said 50 alternate blocks wherein each wale is composed of loose loops, and an additional reinforcing thread knit into each of the loose course areas only.

4. A full-fashioned stocking blank having a 55 leg and instep of normal knitting, a reinforced heel part, a reinforced sole part, a reinforced toe part, one or more of said parts having portions adjacent the outer edges of said blank and extending the full length of the said part or parts wherein each wale is composed of loose loops and 60 having within said part or parts alternate blocks having all loose knit loops and intermediate blocks having all tight knit loops, and an additional reinforcing thread knit into each of the loose loop areas only.

5. A full-fashioned stocking blank having a 70 leg and instep of normal knitting, a reinforced heel, sole and toe, said reinforced sole having 70 portions adjacent the outer edges thereof and extending the full length of said reinforced sole wherein each wale is composed of loose loops and having the balance of said reinforced sole made up of alternate blocks having all loose knit loops 75

- and intermediate blocks having all tight knit loops.
6. A full-fashioned stocking blank having a leg and instep of normal knitting, a reinforced heel, sole and toe, said reinforced sole having portions adjacent the outer edges thereof and extending the full length of said reinforced sole wherein each wale is composed of loose loops and having intermediate said loose wale portions alternate blocks having all loose knit loops and intermediate blocks having all tight knit loops.
7. A full-fashioned stocking blank having a leg and instep of normal knitting, a reinforced heel, sole and toe, said reinforced sole having portions adjacent the outer edges thereof and extending the full length of said reinforced sole wherein each wale is composed of loose loops and having the balance of said reinforced sole made up of alternate blocks having all loose knit loops and intermediate blocks having all tight knit loops, and an additional reinforcing thread knit into each of the loose loop areas only.
8. A full-fashioned stocking blank having a leg and instep of normal knitting, a reinforced heel, sole and toe, said reinforced sole having portions adjacent the outer edges thereof and extending the full length of said reinforced sole wherein each wale is composed of loose loops and having intermediate said loose wale portions alternate blocks having all loose knit loops and intermediate blocks having all tight knit loops, and an additional reinforcing thread knit into each of the loose loop areas only.
9. A full-fashioned stocking blank having a leg and instep of normal knitting, a reinforced heel part, a reinforced sole part, a reinforced toe part, one or more of said parts having portions adjacent the outer edges of said blank and extending the full length of the said part or parts wherein each wale is composed of loose loops and having within said part or parts alternate blocks having all loose knit loops and intermediate blocks having all tight knit loops, and additional reinforcing thread knit into one or more of the loose loops areas only.
10. A full-fashioned stocking blank having a leg and instep of normal knitting, a reinforced heel, sole and toe, said reinforced sole having portions adjacent the outer edges thereof and extending the full length of said reinforced sole wherein each wale is composed of loose loops and having intermediate said loose wale portions alternate blocks having all loose knit loops and intermediate blocks having all tight knit loops, and an additional reinforcing thread knit into one or more of the loose loop areas only.
